UNITED STATES PATENT OFFICE

99,042

DESIGN FOR A PORTABLE COMPRESSOR

Win W. Paget, Michigan City, Ind.

Application August 2, 1935, Serial No. 57,910

Term of patent 14 years

To all whom it may concern:

Be it known that I, Win W. Paget, a citizen of the United States, residing at Michigan City, in the county of LaPorte and State of Indiana, have invented a new, original, and ornamental Design for Portable Compressors, of which the following is a specification, reference being had to the accompanying drawing, forming a part thereof.

Fig. 1 is a top plan view of the article showing my new design.

Fig. 2 is a side elevational view thereof.

Fig. 3 is a rear end view of the same.

Fig. 4 is a front end view thereof.

I claim:

The ornamental design for a portable compressor, as shown.

WIN W. PAGET.
